UNITED STATES PATENT OFFICE.

HARRY G. LEE, OF TACOMA, WASHINGTON.

ELEVATOR SIGNALING SYSTEM.

1,255,026.

Specification of Letters Patent. Patented Jan. 29, 1918.

Application filed March 29, 1915. Serial No. 17,654.

To all whom it may concern:

Be it known that I, HARRY G. LEE, a citizen of the United States, and a resident of Tacoma, in the county of Pierce, State of Washington, have invented certain new and useful Improvements in Elevator Signaling Systems, of which the following is a specification.

This invention relates to devices and electric circuits for use in operating elevators in office and other buildings and has for its objects to provide means whereby, irrespective of the number of elevators operated in the building, any elevator will receive a signal when approaching the floor on which a passenger is waiting; whereby when an elevator has reached the said floor and is traveling in the desired direction, the signal is canceled; whereby the direction of motion of an approaching elevator is indicated on each floor, but receding elevators are not thus indicated; and whereby the elevator operator may cut his cage out of circuit if he does not wish to stop at any floor as, for instance, when his cage is full, thus causing the signal to act on the next following elevator. Other objects are to provide a compact and easily inspected apparatus, which is simple and effective in its action, and cheap to make and install.

I attain these and other objects by the devices, mechanisms, circuits and arrangements illustrated in the accompanying drawings, in which—

Figure 1 is a diagrammatic view of my apparatus and its electric circuits, showing it equipped for three elevators traveling five stories, one such elevator being shown starting down from the fifth floor, another starting up from the first floor, and the third approaching the third floor on its way downward; Figs. 2, 3 and 4 are respectively, front, side, and rear elevations of the controlling board; Fig. 5 is a perspective view of the elevator-signal switch, signal circuit-breakers, and floor-light circuit-breakers; Fig. 6 is a similar view of the reversing switch; and Fig. 7 is a similar view of one of the floor-magnets.

Similar numerals and letters of reference refer to similar parts throughout the several views.

This apparatus consists of the following parts, each of which will be separately described and then their connecting circuits will be described and their operation briefly

stated: On each floor of the building there will be provided a pair of push buttons, the "up" button to be pushed to stop the up-traveling car while the other or "down" button is to be pushed to stop the down-traveling car; also opposite each elevator shaft a pair of lights are mounted, preferably one above the other, the upper light to be lighted when the upward moving car is approaching that floor while the lower light is lighted when a downward moving car is approaching the floor. On each elevator car there is a light which will be lighted when the car is one floor distant from the floor on which the signal button has been pressed to stop a car traveling in its direction; and a switch by means of which its connections may be broken. In the engine room, or other suitable location, is mounted the controlling board on which are secured the sets of floor-magnets, there being one pair fewer than the number of floors at which stops may be made; a reversing switch for each elevator, and operated thereby; a floor-signal and floor-light circuit breaker for each elevator, and operated thereby; and an elevator-signal switch, and operated thereby.

Referring to the drawings, the elevators are indicated by the letters X, Y and Z respectively, and each is provided with a signal light and a cut-out switch in the car; with a pair of floor-lights at each floor of the building, adjacent to its shaft; mechanism (not shown) whereby the elevator is operated; an elevator-signal switch 400 operated by said elevator-operating mechanism in accordance with the position and direction of motion of the elevator in the shaft; a pair of sets of circuit-breakers 200 having separable contacts, one set being in the "up" circuits and the other in the "down" circuits, and set in motion by and with the elevator-signal switch 400; and a reversing switch 100 governed by the direction of motion of the elevator. A single controlling board is provided for all the elevators, said board having two sets of floor-magnets 7 mounted thereon, one for the "up" circuits and the other for the "down" circuits.

Referring first to the push-buttons on each floor, these are not illustrated in detail, but only diagrammatically in Fig. 1, since any of the well known devices for the purpose may be used. The wire "A" from the main line is connected to the switch arm 1

which may connect with either of two contacts 2 and 3. The contact 2 is connected by the wire "B" to the circuit "H" joining the down main magnet armature for that 5 floor with the floor-signal circuit-breaker 200 for that floor, while the contact 3 is correspondingly connected by the wire "C" to the corresponding up circuit "H." On the first floor I provide only a single up button 10 but I connect said button to the down side cable "B," while on the top, or in this case the fifth, floor I provide a single down button which is however connected on the up side cable "C."

15 The floor-lights 4 are also illustrated diagrammatically. The circuit "D" for each light passes from the proper part of the reversing switch 100, through the circuit-breaker magnet 30, in series, through the 20 light 4 then through the floor-light circuit-breaker 300 to the main line.

25 The signal lights 5 on the elevator cars are also indicated diagrammatically in the drawings. The circuit "E" for each car leads from the main line, through the signal light 5, to the elevator signal switch 400. The elevator cut-out switch 6 on the car is of any of the well known forms suitable for the purpose and is connected by the wires 30 "F" on one side to the main line and on the other side to the reversing switch 100 for that car.

35 The floor magnets 7 (Figs. 2 and 7) are mounted on the control board 8. These magnets are in two sets, one set controlled by the up push buttons and the other set by the down push buttons. All the magnets are similar and are connected to corresponding circuits; therefore a description 40 of one will be understood to apply to all. The magnet 7 which is energized when the up button on the first floor is pushed is the down magnet marked for the first floor, but the up buttons on the second, third, etc., 45 floors energize the corresponding up magnets 7. Similarly the down button on the top floor energizes the up magnet 7 marked for that floor but the other down buttons on the fourth, third, etc., floors energize the 50 corresponding down magnets 7. One terminal of each such magnet 7 is connected to the negative bus-bar 9, while the other terminal thereof is connected to the circuit "G" which passes therefrom through the 55 respective floor circuit-breakers 200 of the different elevators in series and back by the circuit "H" to the armature contact 10 of said magnet. The armature 11 of each magnet 7 has two contacts, 10 and 12, thereon 60 the one, 10, connected as above, while the other, 12, is connected by the circuit "I" to the reversing switch 100. Said contacts 10 and 12 are adapted to engage contacts 13 connected to the positive bus-bar 14 when 65 their respective magnets are energized.

One reversing switch 100 (see Fig. 6) is provided for each elevator, said switch consisting of a pivot bar 15 suitably supported and carrying insulated contact fingers 16 thereon, there being as many such fingers 70 on each pivot bar 15 as there are spaces between the floors of the building, said fingers 16 being electrically connected by the circuits "J" to the respective segments of the elevator-signal switch 400. The fingers 16 75 are adapted to contact with the respective terminals 17 of the circuits "I" leading to the armature contacts 12 of the respective up or down floor-magnets 7 as above described. The said terminals 17 on the up 80 and down sides of the reversing switch are arranged in rows, one on each side of the central pivot 15, and in corresponding positions thereon so that each finger 16 will engage a terminal 17 when it is in either position. It will be noticed that the first up floor-magnet 7 is marked for the second floor and that the first down magnet 7 is correspondingly marked for the first or lowest floor, and that the first finger 16 of the 85 reversing switch engages either of the contacts 17 for these two magnets 7 according to whichever position it may be in, and that correspondingly, the next higher finger 16 can engage either the third up or the second 90 down contacts 17, and so on, thus lighting the signal light 5 in the elevator at the moment when the arm of the elevator signal switch has reached the place corresponding with the floor above, if it is traveling downward, and when the arm has reached the place corresponding with the floor below if it is traveling upward. The corresponding terminals 17 of all the reversing switches are connected together in parallel by the 100 circuits "I." An additional finger 18 is also mounted on said pivot bar 15, said finger 18 being adapted to engage the up or down terminal 19 of the circuit "D" which passes through the circuit-breaker magnet 110 30 to the up or down floor-lights 4, and said finger 18 is connected by the wire "F" to the main electric line through the cut-out switch 6 in the elevator cage. Each pivot bar 15 has a grooved wheel 20 mounted on 115 its end and a belt 21 passes over said wheel 20 and is operated by the elevator as hereinafter described. This belt 21 is comparatively loose and slips freely on said wheel 20, so that when the elevator reverses its 120 motion it reverses the motion of the belt 21 and this causes the pivot bar 15 to turn and raise all the fingers 16 and 18 off their terminal contacts 17 and 19 and swing them to the contacts on the other side of the line. When they thus engage the said contacts 17 125 and 19 on the other side of the switch, the pivot bar 15 can turn no farther and the belt 21 continues to slip in said grooved wheel 20 until its motion is again reversed. 130

The circuit-breakers 200 for the floor-signals for each elevator are illustrated particularly in Fig. 5. The gear 22 on the back of the board 8 meshes with the gear 23 which is actuated by the elevator mechanism. The above-mentioned belt 21 engages and is driven by a grooved wheel which is mounted on the same shaft as said gear 23 and turns therewith. A pinion 24 is mounted on the shaft 25 of said gear 22 and meshes with a rack 26. This rack 26 is mounted on a board 27 which is supported and guided by a horizontal bar 28, so that the position of the board 27 on the bar 28 will change with the motion of the elevator. A double row of insulated spring contacts 29 are mounted adjacent each edge of said board 27, said contacts 29 being arranged in pairs and touching each other adjacent their ends. One pair of such contacts 29 are provided for each floor-magnet 7, those for the up magnets being arranged on one side or edge of the board 27 and those for the down magnets 7 being arranged on the other side or edge of the said board. The wires "K" from said spring contacts 29 connect to the corresponding contacts 29 for the adjacent elevators so that all the contacts 29 for one floor magnet 7 are connected together in series and one end of said series is connected by the circuit "G" to one terminal of said floor magnet 7, while the other end of the series is connected by the circuit "H" to the armature 11 of the said floor magnet 7. A pair of magnets 30 are mounted below said spring contacts 29 and are provided with suitable insulating shoes 31 secured to their armatures 32, each such shoe 31 being adapted, when its respective magnet 30 is energized, to pass between the spring contacts 29 forming a pair, as it moves therepast and thus separate them and break the circuits "G", "K" and "H". These circuit-breaking magnets 30 are mounted in the circuit "D" connecting the reversing switch terminals 19 with the up or down floor-lights 4, respectively.

The floor-lights circuit-breaker 300 is also particularly illustrated in Fig. 5. A pending carrier 33 is also secured to the traveling board 27, and said carrier is provided with two series of contacts 34, one above the other, said contacts 34 being connected to the common return wires of the circuits "D" of the respective floor-lights 4. A conductor plate 35 is mounted on the armature 32 of one of the circuit-breaking magnets 30, in such position as to connect with the upper series of contacts 34 when the armature 32 is up and with the lower series when the armature is down, and said conductor 35 is electrically connected to the negative side of the main line. As shown in the drawings, the circuit-breaking contacts 34 for the down side are not placed directly

over those on the up side but are arranged so that the lights above the floor which the elevator is passing are lighted if it is going upward but those below it are lighted if it is going down. 70

The elevator signal switch 400 is also illustrated in Fig. 5. It consists of an arm 36 secured to the spindle 37 of the above-mentioned gear 23, which is actuated by the elevator mechanism. This arm 36 has a brush 38 thereon in constant contact with an inner ring 39 and with a series of segmental insulated contacts 40, one such segmental contact 40 being provided for each space between floors. The said inner ring 39 is electrically connected by the circuit "E" to the signal lamp 5 in the elevator cage while the said segmental contacts 40 are each connected to different fingers 16 of the above-described reversing switch 100 (Fig. 6) by the circuits "J". 80

We will now briefly follow the action of the various parts and circuits:—The positive main line is connected to the common wire "A" for all the floors, and at each floor 90 said current passes through the push-button switch, when the button is pressed, to either of two cables or groups of wires "B" or "C", the one leading to the up circuit "H" and the other leading to the down circuit 95 "H". These wires lead individually from their respective floors to the proper circuit "H" and thence to the proper pair of spring contacts 29 in the circuit-breakers 200 for one elevator, and then by the circuits 100 "K" through all the corresponding contacts 29 of the other elevators in series, and then pass into another cable or group of wires "G" and thus to their respective floor-magnets 7 and thus to the negative 105 bus-bar 9. As soon as the circuit is thus completed through one of the push buttons, the corresponding floor-magnet 7 is energized and the armature 11 thereof is raised so that its contacts 10 and 12 engage the two 110 fixed contacts 13 on the positive bus-bar 14. The current then flows through one such contact 10 and therefrom through the cable 115 "H" to the corresponding spring contacts 29 of the circuit-breaker 200 thence through the circuits "K" and the corresponding contacts 29 of the other circuit-breakers 200 in series, and thence by the circuit "G" through the same floor-magnet 7, thus holding the armature 11 in such contact although the push button may be no longer pressed, and thence to the negative bus-bar 9. The current also flows through the other armature contact 12 by the circuit "I" to the corresponding terminal 17 on the up 120 or down side, as the case may be, of each of the reversing switches 100, in parallel, and if any of the elevators is moving in the said direction, the current flows through the finger 16 which is in contact with that part 130

ticular terminal 17 and passes by the circuit "J" therefrom to the proper segment 40 of the elevator-signal switch 400, and when the arm 36 of said switch moves into 5 contact with the said segment 40, then the current flows therethrough to the circular ring 39 and thence by the circuit "E" to the signal light 5 in the elevator cage, and thence to the negative main line. When any 10 one of the elevators reaches the floor on which the push button has been pressed and is traveling in the right direction, the shoe 31 of its circuit-breaker 200 passes between the contacts 29 and thus breaks the circuits 15 "G," "K" and "H" and demagnetizes the floor-magnet 7, thus breaking the circuit "I" at the contact 12, thus killing the corresponding contacts 17 of the reverse switches 100 of all the elevators, the circuits 20 "J" of each elevator, the segment 40 of each of the elevator signal switches 400, and the signal light 5 and its circuit "E" of that elevator, and restoring the apparatus to its normal uncharged condition.

25 The current for lighting the floor lights 4 for each elevator, passes from the positive main line by the wire "F," through the cut-out switch 6 on the elevator, thence to the finger 18 on the reversing switch 100 for 30 that elevator, thence through the up or down contacts 19 and by the circuit "D" through the circuit-breaker magnet 30, the up or down magnet 30 as the case may be, thence through the up or down floor-lights 35 4 in parallel on each floor, thence to the spring contacts 34 of the floor-light circuit-breaker 300 and through the conductor plate 35 thereof to the negative main line. It is evident that when the cut-out switch 6 is 40 turned to break the circuit "F," that neither of the circuit-breaker magnets 30 will be energized and that therefore the circuits "G," "K" and "H" of the signal system will not be broken by that particular elevator 45 cage as it passes the floor on which one of the buttons has been pushed; also the floor-lights 4 for that elevator will be darkened and will not indicate that the elevator is approaching. The elevator cage "X" in 50 Fig. 1, is indicated as traveling downward with its cut-out switch 6 thus turned. It is also evident that if an elevator cage is traveling upward, the down side of the reversing switch 100 being dead, none of the down 55 lights 4 will be lighted (except the top light which is wired as an up light) and that all (or any desired number) of up lights 4 will be lighted in advance of the elevator cage, but that as soon as the cage has 60 passed a floor the conductor plate 35 of the floor-light circuit-breaker 300 leaves the contact 34 for that floor and thus cuts out the light thereon so that none of the lights on the floors from which the cage is receding 65 are lighted. The up light of the first

floor is wired as a down light and therefore shines as the cage is approaching it downward, and the down light on the top floor is wired as an up light for a similar purpose.

Having described my invention, what I 70 claim is:

1. In an elevator signaling system in a building having a plurality of floors, the combination with a source of electric energy; of a plurality of circuits each including a 75 manually operated signal switch positioned on one floor intermediate between the terminal floors and an electromagnet, the ends of said circuit being connected to the opposite terminals of the source of electric energy; a plurality of alternate circuits, one for each said first circuits and each including a contact switch adapted to be closed by the action of a current in said electromagnet, one end of each alternate circuit 80 being connected to the corresponding first circuit between the manually operated switch and the electromagnet therein and the other end thereof being connected to the same side of the source of electric energy to which 85 said manually operated switch is connected, whereby when said manually operated signal switch of any of said first circuits is closed an electric current will energize the electromagnet of said circuit, and whereby 90 when said electromagnet is thus energized said alternate circuit is closed and the current for said electromagnet flows therethrough; a plurality of circuit breakers one positioned in each of said first circuits between the source of electric energy and said electromagnet, whereby when said circuit is 95 broken by an elevator said magnet is demagnetized and said contact switch is opened; and elevator operated means for operating 100 said circuit-breakers in succession at positions corresponding with the successive floors 105 of the building.

2. In an elevator signaling system, the combination with a source of electric energy; 110 of a circuit including a manually operated signal switch and an electromagnet, the ends of said circuit being connected to the opposite terminals of the source of electric energy; an alternate circuit including a contact switch adapted to be closed by the action of a current in said electromagnet, one end of said alternate circuit being connected to said first circuit between the manually operated switch and the electromagnet therein 115 and the other end thereof being connected to the same side of the source of electric energy to which said manually operated switch is connected, whereby when said manually operated signal switch is closed 120 an electric current will energize said electromagnet, and whereby when said electromagnet is thus energized said alternate circuit is closed and the current for said electromagnet flows therethrough; spring con- 125 130

5 tacts positioned within the circuit between the source of electric energy and said electromagnet, said contacts being normally in contact with each other but being adapted to be separated and thus to break the magnet circuit and open the contact switch; means operated by the elevator whereby said spring contacts are moved in one direction or the other on a defined path in proportion 10 to the motion of said elevator; a circuit-breaker control-circuit connected at its ends to said source of electric energy; a switch in said control-circuit, said switch being operated by the elevator whereby said circuit 15 is closed when the elevator is traveling in one direction but is open when it is traveling in the opposite direction; a second electromagnet in said control-circuit; and a circuit-breaking shoe mounted on and controlled 20 by the armature of said second electromagnet and adapted to enter the path of motion of said spring contacts when said second electromagnet is energized to separate said contacts and break the said magnet circuit, 25 but to be withdrawn therefrom when said control-circuit is broken by said elevator-operated switch.

3. An elevator signaling system in a building having a plurality of floors comprising, 30 in combination, a source of electric energy; a series of indicating lights, one on each floor intermediate between terminal floors of the building; parallel light-circuits, each having a common terminal and an independent terminal, said independent terminals being grouped adjacent each other, said common terminal being connected to one side of the source of electric energy; and a sliding contact operated by the elevator and adapted 35 to engage simultaneously a plurality of said independent light-circuit terminals and connected to the opposite side of the source of electric energy, and arranged whereby said floor-lights are lighted when said elevator 40 is approaching the respective floors but each light is darkened when the elevator has passed the floor on which it is positioned.

4. An elevator signaling system in a building having a plurality of floors comprising, 50 in combination, a source of electric energy; a series of indicating lights, one on each floor intermediate between terminal floors of the building; parallel light-circuits, each having a common terminal and an independent terminal, said independent terminals being grouped adjacent each other; a direction switch connected to one side of the source of electric energy and to the common terminal of said parallel 55 light-circuits, said switch being operated by the elevator whereby said switch is closed when the elevator is traveling in one direction but is open when it is traveling in the opposite direction; and a sliding contact 60 operated by the elevator and adapted to

engage simultaneously a plurality of said independent light-circuit terminals and connected to the opposite side of the source of electric energy, and arranged whereby said floor-lights are lighted when said elevator 70 is approaching the respective floors but each light is darkened when the elevator has passed the floor on which it is positioned.

5. In an elevator signaling system, the combination with a source of electric energy; 75 of a signal-light-circuit connected at its ends to opposite terminals of said source of electric energy and including a signal-light positioned within an elevator; of an electro-magnetically operated contact switch 80 within said circuit and means for controlling said switch; a direction switch in said circuit, said switch being operated by the elevator whereby said circuit is closed when the elevator is traveling in one direction but 85 is open when it is traveling in the opposite direction; and a floor-switch in said circuit, said switch being operated by the elevator whereby said circuit is closed when the elevator reaches a predetermined position but is open at all other positions, whereby said signal-light is lighted in the elevator when said three switches are closed but is darkened when any of said switches is open. 95

6. In an elevator signaling system, the combination with a source of electric energy; of a magnet circuit including a manually operated signal switch and an electromagnet, the ends of said circuit being connected 100 to the opposite terminals of the source of electric energy, said electromagnet controlling a signal-light circuit to close it when the electromagnet is energized; spring contacts positioned within the first circuit between the source of electric energy and said electromagnet, said contacts being normally 105 in contact with each other but being adapted to be separated and thus break the magnet circuit and open the signal-light circuit; a circuit-breaker-control circuit connected at 110 its ends to said source of electric energy; a switch in said circuit-breaker-control circuit, said switch being operated by the elevator whereby said circuit is closed when the elevator is traveling in one direction but is open when it is traveling in the opposite direction; a second electromagnet in 115 said circuit-breaker-control circuit; a circuit-breaking shoe mounted on and controlled by the armature of said second electromagnet; and means operated by the elevator whereby said spring contacts and said circuit-breaking shoe are given a relative motion and whereby when said second electromagnet is energized and said shoe is thus moved into the path of relative motion of said spring contacts said shoe will 120 separate said contacts as they move therepast and break the said magnet-circuit. 125

7. In an elevator signaling system, the combination with a source of electric energy; of a magnet-circuit, including a manually operated signal-switch and an electromagnet, the ends of said circuit being connected to the opposite terminals of the source of electric energy; a signal-light circuit connected at its ends to opposite terminals of said source of electric energy and including 5 a signal-light positioned within an elevator; a contact-switch within said signal-light circuit and operated by the electromagnet within said magnet-circuit, whereby when said magnet is energized said contact-switch is closed; a direction-switch in said signal-light circuit, said switch being operated by the elevator whereby said switch is closed when the elevator is traveling in one direction but is open when it is traveling in the opposite 10 direction; and a floor-switch in said signal-light circuit, said switch being operated by the elevator whereby said switch is closed when the elevator reaches a predetermined position but is open at all other positions, 15 whereby said signal-light is lighted in the elevator when said last three switches are closed but is darkened when any of said switches is open.
8. In an elevator signaling system, the combination with a source of electric energy; of a magnet-circuit including a manually operated signal-switch and an electromagnet, the ends of said circuit being connected to the opposite terminals of the 20 source of electric energy; a signal-light circuit connected at its ends to opposite terminals of said source of electric energy and including a signal-light positioned within an elevator; a second contact-switch within said signal-light circuit and operated by the electromagnet within said magnet-circuit, whereby when said magnet-circuit is energized said second contact-switch is closed; a direction-switch in 25 said signal-light circuit, said switch being operated by the elevator whereby said switch is closed when the elevator is traveling in one direction but is open when it is traveling in the opposite direction; a floor-switch in said signal-light circuit, said switch being operated by the elevator whereby said switch is closed when the elevator reaches a predetermined position but is open at all other positions, 30 whereby said signal-light is lighted in the elevator when said last three switches are closed but is darkened when any of said switches is open; and an elevator-operated circuit-breaker positioned 35 between the source of electric energy and said electromagnet, whereby when said circuit is broken by an elevator said electromagnet is demagnetized and both said contact-switches are opened and said alternate-circuit and said signal-light circuit are broken.
9. In an elevator signaling system, the combination with a source of electric energy; of a magnet-circuit, including a manually operated signal-switch and an electromagnet, the ends of said circuit being connected to the opposite terminals of the source of electric energy; spring contacts positioned within said magnet-circuit between the source of electric energy and said electromagnet, said contacts being normally in contact with each other but being adapted to be separated and thus break the magnet-circuit; a circuit-breaker-control circuit connected at its ends to the opposite terminals of the source of electric energy; a direction-switch within said circuit-breaker-control circuit, said switch being operated by the elevator whereby said circuit is closed
10. In an elevator signaling system, the combination with a source of electric energy; of a magnet-circuit, including a manually operated signal-switch and an electromagnet, the ends of said circuit being connected to the opposite terminals of the source of electric energy; an alternate-circuit, one end thereof being connected to said magnet-circuit between the manually operated signal-switch and the electromagnet and the other end thereof being connected to the same side of the source of electric energy to which the manually operated signal-switch is connected; a contact-switch within said alternate-circuit and operated by the electromagnet within the magnet-circuit, whereby when said magnet is energized said contact-switch is closed; a signal-light circuit connected at its ends to opposite terminals of said source of electric energy and including a signal-light positioned within an elevator; a second contact-switch within said signal-light circuit and operated by the electromagnet within said magnet-circuit, whereby when said magnet-circuit is energized said second contact-switch is closed; a direction-switch in said signal-light circuit, said switch being operated by the elevator whereby said switch is closed when the elevator is traveling in one direction but is open when it is traveling in the opposite direction; a floor-switch in said signal-light circuit, said switch being operated by the elevator whereby said switch is closed when the elevator reaches a predetermined position but is open at all other positions, whereby said signal-light is lighted in the elevator when said last three switches are closed but is darkened when any of said switches is open; and an elevator-operated circuit-breaker positioned between the source of electric energy and said electromagnet, whereby when said circuit is broken by an elevator said electromagnet is demagnetized and both said contact-switches are opened and said alternate-circuit and said signal-light circuit are broken.
11. In an elevator signaling system, the combination with a source of electric energy; of a magnet-circuit, including a manually operated signal-switch and an electromagnet, the ends of said circuit being connected to the opposite terminals of the source of electric energy; spring contacts positioned within said magnet-circuit between the source of electric energy and said electromagnet, said contacts being normally in contact with each other but being adapted to be separated and thus break the magnet-circuit; a circuit-breaker-control circuit connected at its ends to the opposite terminals of the source of electric energy; a direction-switch within said circuit-breaker-control circuit, said switch being operated by the elevator whereby said circuit is closed

- when the elevator is traveling in one direction but is open when it is traveling in the opposite direction; a second electromagnet in said circuit-breaker-control circuit; a circuit-breaking shoe mounted on and controlled by the armature of said second electromagnet; means operated by the elevator whereby said spring contacts and said circuit-breaking shoe are given a relative motion 5 and whereby, when said second electromagnet is energized and said shoe is thus moved into the path of relative motion of said spring contacts, said shoe will separate said contacts as they move therewith and break the said magnet-circuit; a signal-light circuit connected at its ends to opposite terminals of said source of electric energy and including a signal-light positioned within an elevator; a contact-switch 10 within said signal-light circuit and operated by the electromagnet within said magnet-circuit, whereby when said magnet is energized said second contact-switch is closed; a second direction-switch in said signal-light 15 circuit, said switch being operated by the elevator whereby said switch is closed when the elevator is traveling in one direction but is open when it is traveling in the opposite direction; and a floor-switch in said signal-light 20 circuit, said switch being operated by the elevator whereby said switch is closed when the elevator reaches a predetermined position but is open at all other positions, whereby said signal-light is lighted when 25 said last three switches are closed but is darkened when any of them is open.
11. In an elevator signaling system, the combination with a source of electric energy; of a magnet-circuit, including a manually-operated signal-switch and an electromagnet, the ends of said circuit being connected to the opposite terminals of the source of electric energy; an alternate-circuit, one end thereof being connected to said magnet-circuit 30 between the manually-operated signal-switch and the electromagnet and the other end thereof being connected to the same side of the source of electric energy to which the manually-operated signal-switch is connected; a contact-switch within said alternate-circuit and operated by the electromagnet within the magnet-circuit, whereby when said magnet is energized and contact-switch is closed; spring contacts positioned 35 within said magnet-circuit between the source of electric energy and said electromagnet, said contacts being normally in contact with each other but being adapted to be separated and thus break the magnet-circuit; a circuit-breaker-control circuit connected at its ends to the opposite terminals of the source of electric energy; a direction-switch within said circuit-breaker-control circuit, said switch being operated by the elevator whereby said circuit is closed when 40 the elevator is traveling in one direction but is open when it is traveling in the opposite direction; a second electromagnet in said circuit-breaker-control circuit; a circuit-breaking shoe mounted on and controlled by the armature of said second electromagnet; means operated by the elevator whereby said spring contacts and said circuit-breaking shoe are given a relative motion 45 and whereby, when said second electromagnet is energized and said shoe is thus moved into the path of relative motion of said spring contacts, said shoe will separate said contacts as they move therewith and break the said magnet-circuit; a signal-light circuit connected at its ends to opposite terminals of said source of electric energy and including a signal-light positioned within an elevator; a second contact-switch within said signal-light circuit and operated by the electromagnet within said magnet-circuit, whereby when said magnet is energized said second contact switch is closed; a second direction-switch in said signal-light circuit, said switch being operated by the elevator 50 whereby said switch is closed when the elevator is traveling in one direction but is open when it is traveling in the opposite direction; and a floor-switch in said signal-light circuit, said switch being operated by the elevator whereby said switch is closed when the elevator reaches a predetermined position but is open at all other positions, whereby said signal-light is lighted when 55 said last three switches are closed but is darkened when any of them is open.
12. An elevator signaling system in a building having a plurality of elevators, comprising, in combination, a source of electric energy; a magnet-circuit, including a manually-operated signal-switch and an electromagnet, the ends of said circuit being connected to the opposite terminals of the source of electric energy; a plurality of elevator-operated circuit-breakers within said magnet-circuit between the source of electric energy and said electromagnet, one said circuit-breaker for and operated by each said elevator, whereby said magnet-circuit 60 may be broken by any of said elevators; a plurality of parallel signal-light circuits, one for each elevator, connected at their ends to opposite terminals of said source of electric energy, and each including a signal-light positioned within its elevator; a common contact-switch within all said signal-light circuits and operated by the electromagnet within the magnet-circuit, whereby when the magnet-circuit is energized said contact-switch is closed; a plurality of direction-switches, one for each elevator positioned within the signal-light circuit for that elevator, said switch being operated by its elevator whereby said switch is closed 65 when its elevator is traveling in one direction.

tion but is open when it is traveling in the opposite direction; and a plurality of floor-switches, one for each elevator positioned within the signal-light circuit for that elevator, said switch being operated by its elevator whereby said switch is closed when its elevator reaches a predetermined position but is open at all other positions, whereby the signal-light in any of said elevators will be lighted when said last three switches are closed in any of said parallel signal-light circuits but is darkened when any of said switches is open.

13. An elevator signaling system in a building having a plurality of floors, comprising, in combination, a source of electric energy; a plurality of magnet-circuits, one for each floor of the building, each including a separate electromagnet therein, the ends of each said magnet-circuit being connected to the opposite terminals of the source of electric energy; a plurality of manually operated signal-switches, one in each said magnet-circuit whereby said circuit may be closed and said magnet energized; a floor-switch, having an elevator-operated arm and a plurality of contact sectors, one said sector for each floor of the building, a plurality of contact-switches

each operated by one said electromagnet, whereby when its electromagnet is energized it is closed, one side of all said contact-switches being connected to one side of the source of electric energy; a plurality of sector-circuits, each connecting one of said contact-switches with one of the contact sectors in the floor-switch; a plurality of direction-switches, one in each said sector-circuits, said switches being simultaneously operated by the elevator whereby all said switches are closed when the elevator is traveling in one direction but are open when it is traveling in the opposite direction; a signal-light circuit connected at one end to the elevator-operated arm of the floor-switch and at the other end to the opposite side of the source of electric energy from said contact-switches, and including a signal-light positioned within the elevator; and a plurality of elevator-operated circuit-breakers, one in each said magnet-circuits, whereby the elevator may break each of said magnet-circuits in succession as it travels.
